PLANE SURFACE PIEZO-ELECTRIC LOUD SPEAKER

Filed March 11, 1927

UNITED STATES PATENT OFFICE.

ALEXANDER McLEAN NICOLSON, OF NEW YORK, N. Y., ASSIGNOR TO WIRED RADIO, INC., OF NEW YORK, N. Y., A CORPORATION OF DELAWARE.

PLANE-SURFACE PIEZO-ELECTRIC LOUD SPEAKER.

Application filed March 11, 1927. Serial No. 174,486.

This invention relates to a loud speaker adapted for operation by electric currents and more particularly to a loud speaker comprising a piezo-electric crystal.

5 It has been known for a considerable time that by subjecting certain crystals to pressure, differences in electrical potential between different parts or regions of the crystals may be produced, and that conversely, 10 when differences of potential are applied to different parts of such crystals, they develop stresses or motion in accordance therewith. Such phenomena are termed piezo-electric activity and the crystals exhibiting such 15 activity are termed piezo-electric crystals. Such piezo-electric qualities are not limited to whole crystals but may be manifested by plates or rods cut from the crystals in a suitable manner, as more particularly set forth 20 in my copending application Serial No. 155,902, filed Dec. 20, 1926, entitled "Orientation of component crystals in composite piezo-electric devices". Although such effects may 25 be obtained with crystals of a number of different substances, they are obtained in a marked degree from crystals of the substance known as Rochelle salt or sodium-potassium-tartrate.

An important object of the present invention is to provide a novel and effective loud speaker.

Another object of the invention is to provide a novel loud speaker making use of piezo-electric phenomena. Still a further 35 object of my invention is to provide a loud speaker of high quality, which is relatively simple and inexpensive to construct and reliable in operation.

In carrying out my invention, I may provide 40 a piezo-electric crystal device having electrodes arranged thereon, in a manner to be hereafter explained more in detail, and having conductors connected thereto for impressing on the said electrodes differences in 45 potential corresponding to the sounds desired to be reproduced.

The said crystal device is mounted or secured upon a relatively large and preferably plane surface, such for example, as the top 50 of a table, the vertical wall of a cabinet, or the like, in such manner as to set the said surface into vibration in accordance with the vibrations of the crystal device.

In order to secure the best results, I have 55 found that the crystal should not be directly

attached to any relatively soft material, such as wood or the like, but should be attached to one or more metal plates which in turn are attached to the soft material.

The features of novelty which I believe to be characteristic of my invention are set forth with particularity in the appended claims. My invention itself, however, will best be understood both as to its fundamental principles and as to its practical embodiments by reference to the specification and accompanying drawing, in which:

Fig. 1 illustrates one embodiment of the invention;

Fig. 2 illustrates a second embodiment of the invention; and

Fig. 3 illustrates an application of the invention to a radio set.

As indicated in Fig. 1, a piezo-electric crystal 1 preferably of Rochelle salt may be utilized to set into vibration a relatively large surface of comparatively large mass, such as the top 2 of a table 3, thereby producing sound waves of relatively large power and volume. In this form the crystal 1 is suitably secured at each basal plane to a stress plate 4 of suitable material such as steel. The whole is secured against the under side of the table top 2 by means including bolts 5.

The members 4 may be secured to the crystal 1 by a bolt 4^a passing through the members 4 and the crystal 1, and in addition the crystal may be cemented to the members by Rochelle salt "melt" comprising Rochelle salt from which the desired amount of water has been removed by heating it at a temperature above its melting point.

Suitable electrodes are provided which may, for example, take the form of an equatorial belt electrode 6 of metal foil or graphite paint forming a loop around the crystal parallel to the basal plane thereof, and constituting one electrode, and a second electrode which may be formed by bolt 4^a or by one or both of the end members or stress plates 4.

The said electrodes are connected to opposite terminals of a source 9 of electrical oscillations of sound frequency, which may, for example be the output terminals of a radio receiver or amplifier or an electric phonograph.

The crystal 1 will be set into vibration by the electrical oscillations, which vibrations will be transmitted through the stress plates 4 to the table top 2, whence they are communicated.

cated to the atmosphere in greatly amplified form. It is to be noted that in the case where the surface to be set into vibrations is wood, or the like, best results are obtained when a 5 metal stress member having a large bearing surface on the wood is interposed between the crystal and the wood. The exact reasons for this phenomenon are somewhat obscure, but apparently the wood is set into vibration only 10 in local zones and the sound produced is lacking in quality and quantity if the crystal is mounted directly thereon, without the interposed metal member. This is probably because the crystal has a high motional impedance and requires a stiff coupling to stress 15 the wood, which is relatively softer.

Referring now to Fig. 2, I have shown a crystal 1 supported on the lower side of plate 11 which may be of metal, secured to a table 20 top 2 by suitable bolts 12. In this form the crystal 1 is secured to the plate 11 by suitable means such as Rochelle salt "melt." In this case, the electrodes of the crystal 1 shown 25 diagrammatically, are connected with source 9 as before. It should be understood that this arrangement is particularly advantageous in that the plate 11 with the piezo-electric crystal mounted thereon may easily be shifted and attached to parts of furniture or other 30 suitable members as desired.

Referring now to Fig. 3, I have shown a piezo-electric crystal 1 and plate 11 such as shown in Fig. 2, attached to a part of the cabinet 13 of a radio receiver 14. In this instance, the plate 11 is bolted or otherwise secured to the inside of the front panel of the receiver cabinet, and the crystal electrodes are connected to the output terminals of the receiver.

40 It will be understood that this arrangement forms a particularly advantageous combination since it provides for an inexpensive loud speaker of very high quality and good sound intensity, of the utmost simplicity to install, 45 which is completely hidden from view, and yet radiates sound in practically all directions.

While I have illustrated only a few embodiments of my invention, for the purpose of 50 describing the same and illustrating its principles of operation, it is apparent that various changes and modifications may be made therein without departing from the spirit and scope of my invention. I desire, therefore, 55 that only such limitations shall be imposed as are indicated by the prior art, or are specifically set forth in the appended claims.

I claim:

60 1. A loud speaker comprising a sound reproducing surface, a piezo-electric crystal device adapted to be vibrated by electrical oscillations of sound frequency, a metallic plate positioned parallel thereto, means con-

necting opposite ends of said crystal device 65 with said plate, and a bearing surface on said plate arranged for connection with said sound reproducing surface.

2. A loud speaker comprising a sound reproducing surface, a piezo-electric crystal device adapted to be vibrated by electrical oscillations of sound frequency, and a metal plate secured to said sound reproducing surface, said plate having a relatively large bearing surface co-extensive with said sound reproducing surface and connections between a plurality of points on said crystal device 75 and said plate.

3. A loud speaker comprising a sound reproducing surface, a piezo-electric crystal device adapted to be vibrated by electrical oscillations, a metal plate connected through a plurality of independent points with said plate, said crystal device being arranged to be mounted on said sound reproducing surface with the axis of said crystal parallel 80 thereto whereby vibrations from said crystal are imparted to said sound reproducing surface.

4. A loud speaker comprising a sound reproducing surface, a piezo-electric crystal device adapted to be vibrated by electrical oscillations, a metal plate connected through a plurality of points with said plate, said 85 crystal device being arranged to be mounted upon said sound reproducing surface and to make contact therewith only through said metal plate.

5. In a loud speaker, a wooden member 90 adapted to be set into vibration, a piezo-electric crystal of Rochelle salt adjacent said member, and means including Rochelle salt melt for connecting said crystal with said member at each end thereof.

6. In a loud speaker, a wooden member 105 having substantial lateral and longitudinal area in substantially the same plane adapted to be set into vibration, a metal plate, a piezo-electric crystal spaced from said plate but with its opposite ends connected therewith, 110 and means for detachably connecting said plate with said member for imparting vibrations thereto.

7. A loud speaker element adapted to be connected with a vibratile wooden member 115 and including a metallic supporting plate adapted to be secured to said member, a piezo-electric crystal substantially parallel to said plate but spaced therefrom and supports projecting from said plate and engaging the opposite ends of said crystal for transferring 120 the vibrations of said crystal to said vibratile member.

Signed at New York, in the county of New York and State of New York this tenth day of March A. D. 1927.

ALEXANDER McLEAN NICOLSON.
